HYDROPNEUMATIC VALVE.

1,072,562.

Specification of Letters Patent.

Patented Sept. 9, 1913.

Application filed March 13, 1913. Serial No. 753,961.

To all whom it may concern:

Be it known that I, LOUIS DE LISSA BERG, a citizen of the United States, residing at Watertown, in the county of Jefferson and State of New York, have invented certain new and useful Improvements in Hydro-pneumatic Valves, of which the following is a specification.

This invention relates to improvements in hydro-pneumatic valves, and has for its object to provide a novel, simple and effective device of the class, wherein a three-way cock for controlling air or other fluid-pressure is combined with a water or other liquid discharge or lift; the said features being embodied in a one-part body, which is capable of being attached to a suitable liquid container, for lifting and discharging the liquid under pressure, for sprinkling or other purposes.

The advantages and features of the invention are fully set forth in the detailed description which follows; wherein reference is made to the accompanying drawing, in which—

Figure 1 is a top plan view of my improved valve. Fig. 2 is a central vertical section taken on line 2—2 of Fig. 1, showing the valve in the act of lifting and discharging the water from the retainer. Fig. 3 is a similar view; showing the valve in position for exhausting the lifting pressure from the retainer. Fig. 4 is a horizontal section, taken on line 4—4 of Fig. 3.

In the drawing, 2 represents the body of my improved valve, which is in one part, and which consists of a pressure inlet neck 3, which is preferably internally threaded to receive an air or other fluid-pressure supply pipe 4, by means of which the pressure is supplied through a port 5, to a chamber 6, in which is disposed a three-way valve 7, which when operated and set, by a handle 8, in the position shown in Fig. 2, allows the air pressure to pass downwardly through a port 9, for performing its work. 10 represents a water or other container preferably in the form of a cylindrical tank, which has a flanged-top 11 for supporting the tank when in use. The top 11 of the container is provided with a central threaded opening 12 to receive a depending screw-threaded neck or portion 13 of the body 2. 14 represents an angular port or passage, a part of which is disposed in the neck 13 of the body parallel to the port 9, the lower

end of which is counter-bored and threaded to receive the upper end of a feed-pipe 15, which is disposed in, and extends to within a short distance of the bottom of, the retainer 10. The upper extremity of the port 14 comprises the bore of a discharge neck or nozzle 16, which is a part of the body 2, and which alines with and faces oppositely to, the inlet neck 3. The free end of the nozzle 16 is preferably tapered to facilitate the attaching of a hose or like part 17. In carrying out the objects of my invention, the retainer or tank 10 which supports the valve body 2, may be inserted vertically in another tank, as 18, which carries a supply of water or other fluid 19, the tank 18 being suitably perforated at 20 for receiving the retainer, and the latter is then held in place by bolts 21 which pierce the flange of the top 11 and are threaded into the top of the tank 18.

Various means may be employed for admitting the water 19 into the retainer 10, to be discharged through the pipe 15 and the nozzle 16, but I prefer to use an automatic ball-check-valve, which is inserted in a suitable opening in the side, near the bottom, of the retainer, as shown in Figs. 2 and 3.

The check-valve in the present case, consists of a hollow caged-body 22, which has external threads for screwing into the retainer 10, and in which is disposed a free ball 23. 24 represents a bushing, which is threaded into the outer end of the cage 22, and which has a clear longitudinal opening for the passage of the water from the tank 18 into the retainer 10, when the ball 23 is in the position shown in Fig. 3.

The operation of my hydro-pneumatic valve is as follows: Assuming that the valve 7 and the other parts are in the positions shown in Fig. 3, wherein the water in the retainer 10 and the tank 18 is at a common level, owing to the check-valve being open, to obtain the water from the retainer for sprinkling or other purposes, the operator shifts the handle 8 from the horizontal positions shown in Figs. 1 and 3, to the vertical position shown in Fig. 2, which partially rotates the valve plug 7, for allowing the air pressure carried by pipe 4 to pass through the said plug, thence downwardly through port 9 into the top of the retainer. When the air enters the retainer, it exerts a sufficient pressure to force the

ball 23, from the idle position, resting on the bottom of the cage 22 (see Fig. 3), into the seat 26 in the inner end of the bushing 24, which prevents any of the water from escaping from the retainer into the tank 18. As soon as the check-valve is closed, the force of the air pressure lifts the water in the retainer upwardly through the pipe 15, port 14, and discharges the water through the nozzle 16. When sufficient water has been forced or lifted out of the retainer, the operator should reverse the handle 8, to the position shown in Fig. 3, which allows the pressure remaining in the retainer above the water to escape or exhaust through the port 9, plug 7, and an exhaust port 27. Immediately the pressure is exhausted, as described, the ball 23 will gravitate away from its seat at the end of the bushing 24, which will allow the recharging of the retainer through the said bushing.

Having thus described my invention, what I claim as new and desire to secure by Letters Patent, is—

- 25 1. A hydro-pneumatic valve, comprising a body having a valve-chamber therein, and having a pressure-inlet and a pressure outlet port communicating with said chamber, said body having a liquid-discharge passage, one portion of said passage disposed parallel to the pressure-outlet port, the other portion of said passage comprising the bore of a nozzle, a rotatable three-way valve-plug disposed in said chamber adapted to control 30 the admission, as well as, the exhaust of the pressure, and a handle for operating said valve-plug.
- 35 2. The combination with a tank for containing liquid, said tank having a threaded opening in its top, of a valve connecting with the opening of the tank, said valve comprising a body having a pressure inlet port leading to a valve-chamber, and a port leading from said chamber to the tank, said 40 body having a liquid discharge port, one end of said port communicating with said tank, the other end of said port comprising the bore of a nozzle, a three-way valve-plug in said chamber adapted to control the 45 passage of the pressure to and from the said tank, a handle for operating said plug, and

a pipe connected with the liquid discharge port adapted for drawing liquid from the bottom of said tank.

3. In combination, a tank for containing liquid, said tank having a threaded opening in its top and a liquid inlet port near its bottom, a valve, said valve connecting with the opening in the tank, said valve comprising a body having a pressure inlet port leading 55 to a valve chamber and a port leading from said chamber to said tank, said body having a normally open liquid discharge port, one end of said discharge port communicating with the interior of the said tank, the other 60 end of said discharge port passing through a nozzle, a valve-plug in said chamber adapted to control the inflow and the outflow of the pressure to and from said tank, and a handle for operating said valve-plug. 70

4. In a device of the class described, the combination with a liquid tank having a threaded opening in its top, of a valve-body having a depending neck adapted to be screwed into said opening, said body having 75 a valve-chamber connecting with the interior of the tank by means of a port, said body having an air-inlet-port connecting with said chamber, said body having a liquid-discharge passage in the said depending 80 neck parallel to the first port and communicating with the interior of the tank, said body having a nozzle connecting with said liquid-discharge passage, a pipe connecting with said discharge-passage adapted to draw 85 the liquid from the bottom of the tank, and a three-way-valve in said chamber, said valve adapted for admitting air pressure to the said tank for forcing the liquid through said pipe and said nozzle, said valve capable 90 of being operated for exhausting the air pressure from said tank and for stopping the discharge of the liquid through said nozzle, and means for manually operating said valve. 95

In testimony whereof I affix my signature in presence of two witnesses.
